DESIGN FOR A GAME BOARD

William Louis Flacks, Chicago, Ill.

Application March 27, 1940, Serial No. 91,269

Term of patent 3½ years

To all whom it may concern:

Be it known that I, William Louis Flacks, a citizen of the United States and resident of Chicago, in the county of Cook and State of Illinois, have invented a new, original, and ornamental Design for a Game Board, of which the following is a specification, reference being had to the accompanying drawing, forming a part thereof.

The drawing discloses approximately one-half (½) of the game board, it being understood that the design applied to the complementary portion of the board is a repetition and a duplicate of the design shown.

I claim:

The ornamental design for a game board, substantially as shown and described.

WILLIAM LOUIS FLACKS.
